UNITED STATES PATENT OFFICE.

LAURENCE E. TOPHAM, OF SWAMPSIDE, MASSACHUSETTS, ASSIGNOR TO UNITED SHOE MACHINERY CORPORATION, OF PATERSON, NEW JERSEY, A CORPORATION OF NEW JERSEY.

SEWING MACHINE.

Application filed April 29, 1918, Serial No. 231,335, and in Canada April 8, 1918. Renewed July 14, 1922.
Serial No. 574,979.

This invention relates to sewing machines. regarded as limited, however, to hook needle 55

Certain features of the invention are particularly advantageous when embodied in lockstitch machines employed in sewing a 5 series of seams all of substantially the same length, such as machines for sewing outsoles to the welts of welted shoes. In machines of this class heretofore devised the operator cannot determine when the supply of thread 10 on the bobbin is running low without removing the bobbin from the bobbin holder, and it is a common practise to run such machines until the bobbin thread is actually exhausted. In sewing outsoles to the welts 15 of welted shoes the operator often starts a seam without having enough thread on the bobbin to complete the seam, with the result that the bobbin thread becomes exhausted before the seam is finished. When this 20 occurs the operator ejects the exhausted bobbin by an actuation of the hand bobbin ejector lever, inserts a full bobbin in the bobbin holder, and then adjusts the work in the machine so that the needle in forming the first 25 stitch will pass through the needle hole at the end of the last perfect stitch of the part of the seam formed before the exhaustion of the thread. The last part of the seam is started with the work adjusted in this manner 30 so that there will be no break in the seam showing upon the upper surface of the projecting edge of the sole of the finished shoe. After the seam is completed the free ends of the needle and bobbin threads projecting from the work at the point where the two parts of the seam are joined, are trimmed close to the work. This adjustment of the work in splicing the two parts of the seam and the trimming of the threads must be accurately and 35 carefully performed in order that the imperfection in the seam may be hidden when the shoe is finished. These operations, therefore, take considerable time and require some skill. When the work is adjusted, or the threads 40 are trimmed carelessly or unskillfully, the imperfection in the seam can often be easily detected in the finished shoe and greatly impairs the appearance of the shoe.

In its illustrated form the invention is embodied in a machine having a hook needle, a loop taker, and other thread handling devices constructed and arranged to handle waxed thread and operating to form a lock-stitch seam. The invention is not to be

or waxed-thread sewing machines, but it may be embodied with advantage in machines for handling dry thread. In its broader aspects also the invention is not limited to lockstitch machines, but it is also applicable to machines having stitch-forming devices constructed and arranged to form other types of two-thread seams, and also to machines having stitch-forming devices constructed and arranged to form chain-stitch and other 60 single thread seams. It is to be understood, therefore, that except as defined in the claims the invention is not limited to any particular type of machine.

One object of the invention is to produce 70 a sewing machine in which the disadvantage caused by the exhaustion of the thread without forewarning during the formation of a seam will be avoided.

Another object of the invention is to improve the construction and operation of lock-stitch sewing machines with a view of producing a machine in which upon the exhaustion or substantial exhaustion of the thread upon the bobbin, a full bobbin may be substituted for an empty bobbin without unnecessary labor or loss of time.

With these objects in view a feature of the invention contemplates the provision of mechanism for indicating to the operator when the amount of thread left on the thread supply holder is less than a predetermined amount. In the preferred form of the invention the indicating mechanism is rendered active to indicate the condition of the thread supply only upon stopping the machine. Broadly considered, however, this feature may be embodied in indicating mechanisms constructed and arranged to perform this indicating function either during the normal running of the machine or at other suitable or convenient times. With such mechanism under usual conditions the operator is warned of the approach of the end of the thread supply before the thread is actually 75 exhausted. This mechanism also practically ensures that the operator will not start a seam requiring at least the predetermined amount of thread when the supply holder contains less than this amount, and the loss 80 of time of the operator and the production of imperfect work resulting from the exhaustion of the thread before the completion 85 90 95 100 105

of the seam will be avoided. In certain aspects the indicating mechanism of the present invention is not limited to the above feature thereof, and it is to be understood that 5 this mechanism may be embodied in any form within the scope of the claims.

In the present embodiment of the invention the indicating mechanism is applied to a lockstitch machine to indicate when less than 10 a predetermined amount is left on the bobbin. In this embodiment of the invention the indicating mechanism consists of a bobbin ejector mechanism operating automatically to eject the bobbin from the bobbin holder, and the provision in a lockstitch machine of mechanism for automatically ejecting 15 a bobbin from the bobbin holder constitutes another feature of the present invention. This feature of the invention is not 20 to be regarded as limited to a bobbin ejecting mechanism which operates upon stopping the machine or when the supply of thread left on the bobbin is less than a predetermined amount, as in the present embodiment 25 of the invention, but it may be embodied in a bobbin ejecting mechanism having other convenient or suitable times or modes of operation. In a machine provided with mechanism for automatically ejecting the bobbin 30 the substitution of a full bobbin for an empty one may be easily performed and requires much less time than in a machine having the usual hand-operated bobbin ejector.

The features of the invention will be 35 readily understood from the accompanying drawings illustrating the invention in its preferred form, and the following detailed description of the construction therein shown.

40 In the drawings, Figure 1 is a view in front elevation of a portion of the head of a machine embodying the invention; Fig. 2 is a plan view of substantially the portion of the head illustrated in Fig. 1; Fig. 3 is a sectional view of the head of the machine taken in a plane substantially perpendicular to the axis of the main shaft of the machine; Fig. 4 is a view in side elevation, partly in section, illustrating certain parts 45 of the stitch-forming, work-holding and bobbin ejector mechanisms located in the upper forward portion of the machine head; Fig. 5 is a detail plan view, partly in section, illustrating the bobbin ejector mechanisms; Fig. 6 is a view in front elevation, partly in section, of the parts shown in Fig. 5; Fig. 7 is a detail view, partly in side elevation and partly in section, illustrating rotary hook and bobbin ejector mechanisms; Fig. 8 is a view similar to Fig. 7, with certain of the parts illustrated in different positions; Fig. 9 is a view similar to Figs. 7 and 8 with certain of the parts illustrated in still 55 different positions; Fig. 10 is a detail view, partly broken away and partly in section,

taken in the direction of the arrow *a*, Fig. 7, and illustrating the bobbin case, bobbin, and certain associated parts; Fig. 11 is a detail view taken in the direction of the arrow *a*, Fig. 7, and illustrating the bobbin case 70 and certain associated parts, with the bobbin removed from the bobbin case; Fig. 12 is a detail view taken in the direction of the arrow *b*, Fig. 7, and illustrating the bobbin case and certain associated parts, with the bobbin removed from the bobbin case; Fig. 13 is a detail view, similar to Fig. 10, taken at a later stage in the operation of the machine; Fig. 14 is a detail view, partly broken away and partly in section, taken in the direction of the axis of the loop taker, Fig. 8, and illustrating the bobbin case, bobbin, and certain associated parts; and Fig. 15 is a detail view taken in the direction of the axis of the loop taker, Fig. 9, and illustrating the bobbin case and certain associated parts, with the bobbin removed from the 80 bobbin case.

The sewing machine illustrated in the drawings is a curved hook needle lockstitch 90 machine for sewing outsoles to the welts of welted shoes. The machine comprises a curved hook needle 2, a looper 4, a thread finger 6, a loop-taker 8, a thread lifter 10, and a take-up 12, all constructed and arranged to operate to form a lockstitch waxed thread seam. The machine is also provided with a work support 14 and a presser-foot 16. The operating parts of the machine are all driven from a main shaft 18. The parts 100 briefly referred to above in the machine illustrated have substantially the same construction, arrangement and mode of operation as the corresponding parts of the machine illustrated and described in the patent 105 to Fred Ashworth No. 1,169,909, dated February 1, 1916.

The machine is also provided with mechanism for driving the main shaft 18 at high speed during the normal operation of the 110 machine, with mechanism rendered operative upon disconnecting the high speed mechanism from the shaft for slowing down the shaft to a predetermined slow speed and driving the shaft in a forward direction to 115 stopping position, and with mechanism for stopping the shaft in a predetermined definite position. With the exception of certain relatively unimportant changes hereinafter pointed out, these mechanisms have 120 substantially the same construction and arrangement of parts, and substantially the same mode of operation as the corresponding mechanisms of the machine illustrated and described in the patent to Fred Ashworth, 125 No. 1,233,539, dated July 17th, 1917.

The mechanism for driving the main shaft 18 at high speed during the normal operation of the machine (see Figs. 1 and 2) comprises a friction clutch consisting of a driven 130

clutch member 20 fixed to the shaft 18, and a driving clutch member 22 loosely mounted on the shaft and movable longitudinally of the shaft into and out of engagement with the driven clutch member. The driving clutch member is formed with a peripheral groove to receive a belt 24 for connecting said member with a pulley mounted on a power shaft located at the base of the machine and not shown in the drawings. The engagement of the driving member of the clutch with the driven member thereof is controlled by a bell crank lever 26, pivoted on a stud 28, the upper forked end of the vertically extending arm of which embraces the hub of the driving clutch member and carries a pair of pivoted blocks 30 engaging in a groove 32 in the hub of the driving clutch member. Upon the stud 28 is also pivoted an arm 34 having a yielding connection with the horizontally extending arm of the bell crank 26. Through the end of the horizontally-extending arm of the bell crank and through a lateral projection or lug on the arm 34, passes a rod 36, and a coiled spring 38 surrounding the rod is interposed between the lug on the arm 34 and a nut 40 threaded on the lower end of the rod. The end of the arm 34 is formed with a lateral projection indicated at 42 in Fig. 3 which is located between two collars 44 and 46 secured to a treadle rod 48. The upper end of the treadle rod is pivotally connected with an arm 50 pivoted on a shaft 52, and the lower end of the rod is connected with a suitable treadle, not shown. The treadle and treadle rod are elevated upon the release of the treadle by the action of a coiled spring, as in the construction shown in Patent No. 1,233,539.

With this construction, as the treadle rod is depressed the collar 44 engages the lateral projection on the end of the arm 34 and swings the arm downwardly, thereby through the spring 38 actuating the bell crank 26, to carry the driving clutch member 22 into engagement with the driven clutch member 20. The spring allows the arm 34 and the treadle rod to continue their downward movement after the clutch members are engaged, the clutch members then being held in engagement by the force of the spring. The arm 34 is swung upwardly to actuate the bell crank lever to carry the driving clutch member out of engagement with the driven clutch member as the treadle rod is elevated by the action of the treadle actuating spring, by the engagement of the collar 46 with the projection 42 on the arm 34. The upward movement of the arm 34 is limited by the engagement of an abutment screw 54 mounted in the arm, with the frame.

The upward movement of the treadle rod 48 when it is released not only causes the dis-

engagement of the high speed clutch, but also throws into operation the mechanism for slowing down the rotation of the main shaft, and for driving it in a forward direction to stopping position. This mechanism (see Figs. 1, 2 and 3), comprises a slow speed driving clutch member 56 loosely mounted on the shaft, a driven clutch member 58 carried by a sleeve 60 mounted on the shaft to rotate with the shaft and movable longitudinally of the shaft to carry the driven clutch member into and out of engagement with the driving clutch member. The driving clutch member is provided with a series of spiral gear teeth 62 meshing with the teeth of a spiral gear 64 mounted on a continuously rotating shaft 66. The shaft 66 is continuously driven by means of a belt 68 passing about a pulley 70 fixed on the shaft, and about a continuously rotating driving pulley (not shown) located in the base of the machine. The mechanism for controlling the engagement of the slow speed clutch comprises a lever 72 pivoted on the stud 74 and carrying a cam roll 76 at the extremity of its forwardly extending arm engaging in a cam groove 78 in the sleeve 60. Said mechanism also comprises a lock bolt carrier 80 mounted to slide longitudinally in suitable guides in the frame, and carrying at its rear end a lock bolt 82 mounted to slide vertically in the lock bolt carrier, and having its upper end shaped to engage in a recess 84 in the laterally-extending arm of the lever 72. The lock bolt carrier is acted upon by a coiled spring 86 surrounding the carrier and interposed between a shoulder on the carrier and the rear end of a sleeve 88 threaded into the frame through which sleeve the carrier slides. The rearward movement of the carrier under the action of the spring 86 is limited by the engagement of a stop nut 90 mounted on the carrier, with the forward end of the sleeve. The lock bolt 82 is acted upon by a coiled spring 92 which normally tends to force the lock bolt upwardly in the carrier 80 to engage its upper end in the recess in the laterally-extending arm of the lever 72. The position of the lock bolt in the carrier 80 is controlled through suitable connections from the treadle rod. The connections for controlling the position of the lock bolt 82 from the treadle rod comprise the lever 94 pivoted on a stud 96, and a link 98 connecting one arm of the lever with a block 100 secured to the lower end of the lock bolt. Another arm of the lever 94 carries a roll 102 arranged to be engaged by the rear end of the arm 50. As long as the treadle is depressed far enough to maintain the members of the high speed driving clutch in engagement, the lever 94 is held in position to maintain the lock bolt 82 down out of engagement with the recess in the laterally-

extending arm of the lever 72 by the engagement of the roll 102 with the curved face 104 formed at the rear end of the arm 50, which face is preferably struck on an arc having its center in the axis of the arm. Upon the release of the treadle and the elevation of the treadle, treadle rod and arm 50 by the treadle actuating spring, the arm is disengaged from the roll 102, allowing the lock bolt to be moved upwardly by its actuating spring. The upward movement of the lock bolt carries the upward end of the lock bolt into engagement with the lower face of the laterally-extending arm of the lever 72, and when the recess in the arm reaches a certain position the upper end of the lock bolt is engaged in the recess, thereby locking the lever 72 to the lock bolt carrier. With the lever 72 locked to the lock bolt carrier, through the co-operative action of the cam groove 78 and the cam roll 76, the sleeve 60 is moved longitudinally of the main shaft 18 in one direction to engage the driven member 58 of the slow speed clutch 25 with the driving member 56 of the clutch, at one predetermined point in the rotation of the main shaft, is held in position to maintain the members of the clutch in engagement through a predetermined interval 30 in the rotation of the shaft, and is then moved longitudinally of the shaft in the opposite direction to disengage the driven clutch member from the driving clutch member at another predetermined point in the 35 rotation of the shaft. When the members of the clutch are engaged, the driving clutch member first acts as a friction brake to slow down the speed of the driven clutch member and the main shaft until the driven clutch member is rotating at substantially the same speed as the driving clutch member. The driving clutch member then acts to drive the driven clutch member and the shaft at slow speed to stopping position. 40 Upon the disengagement of the members of the slow speed clutch the rotation of the main shaft is arrested at a predetermined point in its rotation by positively acting stopping devices. With the lever 72 locked 45 to the lock bolt carrier when the first incline in the cam groove 78 engages the cam roll 76, the sleeve 60 is first shifted longitudinally of the main shaft to carry the driven clutch member into engagement with the driving clutch member, and the lever 72 is then actuated to move the lock bolt carrier 50 forwardly in its guides against the tension of the spring 86, the members of the slow speed clutch then being held in engagement by the pressure of the spring. When the second incline in the cam groove 55 engages the cam roll 76, the lock bolt carrier is first moved rearwardly in its guides by the action of the coiled spring 86 until its 60 movement is arrested by the engagement of

the stop nut 90 with the end of the sleeve 88, and the sleeve 60 is then moved longitudinally of the main shaft to carry the driven member of the clutch out of engagement with the driving member. 70

The devices for positively stopping the rotation of the main shaft 18 at a predetermined point in its rotary movement upon the disengagement of the members of the slow speed clutch comprise a lever 106 pivoted by means of trunnion pins 108 to a sleeve 110 mounted to turn upon a shaft 112, and a stop projection or lug 114 carried by the main shaft and arranged to engage the end of the arm 116 of the lever 106, to arrest the rotation of the shaft. The main shaft also carries a cam 118 arranged to engage the end of the arm 116 which acts to swing the lever 106 about the shaft 112. The end of the arm 116 may be swung into and out of the path of the cam 118 and projection 114 by swinging the lever 106 about the axis of the trunnion pins 108. The lever 106 is held in position with the end of the arm located out of the path of the cam and projection as 80 long as the treadle rod is depressed by the engagement of an abutment screw 120 threaded into a laterally extending arm 122 on the lever 106 with a forwardly extending arm on the lever 94, as shown in Fig. 3. The lever 106 is swung in a direction to carry the end of the arm 116 into the path of the cam and projection upon the elevation of the treadle rod by the action of a coiled spring 124 connected with the arm 122. 85 With the end of the arm 116 located in the path of the cam 118 and projection 114, through the engagement of the cam with the end of the arm the lever 106 is swung rearwardly about the shaft 112, and the main 90 shaft 18 is finally brought to rest in a predetermined position by the engagement of the projection with the end of the arm. The movement of the lever 106 produced by the action of the cam 118 operates through 95 suitable connections to lift the presser-foot of the machine. A latch is provided to hold the parts in the positions into which they are moved by the action of the cam 118 on the lever 106 and the cam moves out of contact with the end of the arm 116 before the arm is engaged by the projection 114, as shown in Fig. 3, so that the lever 106 may be 100 swung about the axis of the trunnion pins 108 to carry the end of the arm 116 out of the path of the cam and projection by a comparatively light pressure on the treadle. The parts of the machine above described have substantially the same construction, arrangement and mode of operation as the corresponding parts of the machine illustrated and described in the Ashworth patent referred to above. 105

The rotary loop-taker 8 employed in the present machine is of the well-known type 110

constructed and arranged to pass a loop of needle thread about the bobbin case without itself passing through the loop, and known in the art as a "rotary hook." The loop-taker is rotatably mounted in a raceway formed by the supporting plates 126 (see Figs. 4 and 7), secured to the frame of the machine, the plates engaging in a peripheral groove in the loop-taker. The loop-taker is driven (see Figs. 1, 2, 4 and 7), by means of a gear 128 secured to the forward end of a shaft 130 and meshing with a series of gear teeth 132 formed on the periphery of the loop-taker. The shaft 130 is driven from a countershaft 134 through a bevel gear 136 secured to the countershaft and a bevel gear 138 secured to the rear end of the shaft 130. The countershaft 134 is driven from the main shaft 18 through the intermeshing spur gears 140 and 142, secured respectively to the main shaft and to the countershaft. The bobbin case, indicated at 144, is mounted co-axially with the loop-taker in the rear end of the loop-taker so as to allow relative rotation between the bobbin case and loop-taker, the bobbin case having a peripheral flange or rib 146 which engages in a groove formed in the interior wall of the loop-taker. The bobbin case is held stationary during the rotation of the loop-taker by means of retaining pins 148. These pins are slidably mounted forwardly of the bobbin case in a portion 150 of the frame extending within the forward end of the loop-taker so that the rear ends of the pins are adapted to engage in recesses in the bobbin case to hold the bobbin case from rotation. The retaining pins are acted upon respectively by the arms of a spring 152 which tend to move the pins rearwardly to maintain the ends of the pins in the recesses in the bobbin case. The pins are moved forwardly to withdrawn their rear ends from the recesses in the bobbin case at certain times during the rotation of the loop-taker by means of a cam rib 154 projecting from the interior wall of the loop-taker, which is arranged to engage projections 156 formed on the pins. Through the action of the cam rib on the pins during the rotation of the loop-taker, the pins are alternately moved forwardly to withdraw their rear ends from the recesses in the bobbin case to allow a loop of needle thread to pass about the bobbin case. The pins are actuated, however, by the spring 152 and the cam rib 154 in timed relation to each other, so that the rear end of one or the other of the pins is always in engagement with the bobbin case, thereby holding the bobbin case at all times from rotation. A thread tension device 158 consisting of an arc-shaped spring plate is mounted in a peripheral groove in the bobbin case and has one end secured to the bobbin case and the other end free, so that the thread as it passes be-

tween the peripheral face of the bobbin case and the free end of the spring will be pressed by the free end of the spring yieldingly against said face.

The present machine is constructed to employ bobbins in which a length of thread just sufficient to sew a single shoe of a certain size is first wound on the bobbin in one direction, and the remainder of the thread is wound on the bobbin in the opposite direction, as shown in Figs. 10 and 13. With the thread wound in this manner on the bobbin, it will be obvious that as the thread is drawn from the bobbin the bobbin will be rotated in one direction until the point is reached at which the direction of the winding of the thread is reversed, and thereafter the bobbin will be rotated in the opposite direction. The mechanism for indicating the condition of the bobbin thread supply and for ejecting the bobbin is controlled by the direction of rotation of the bobbin, the bobbin ejector remaining inactive during the rotation of the bobbin produced by the drawing of the thread therefrom, until the reversal in the direction of the winding is reached, and being thrown into operation upon the stoppage of the machine following the reversal in the direction of rotation of the bobbin. The bobbin case 144 is formed with a boss 160 projecting centrally from the rear wall of the bobbin case within the same in which is threaded a stud 162. The boss 160 and stud 162 form a support for a sleeve 164 mounted to turn loosely on the boss and stud and adapted to be inserted in the central opening in a bobbin to support the bobbin. Figs. 7 and 8 illustrate clearly the manner in which the bobbin is supported in operating position in the bobbin case. The forward end of the sleeve 164 is slotted at several points, thereby forming a series of yielding projections adapted to engage frictionally the wall of the central opening in the bobbin. The sleeve is formed with a wing 166 projecting therefrom, substantially in the plane of the end wall of the bobbin case, the wing being located in an opening in said wall. The bobbin as it rotates tends to rotate the sleeve therewith through the frictional engagement of the sleeve with the bobbin. During the rotation of the bobbin in the direction of the arrows, Figs. 10, 11, 12 and 13, produced by the drawing of the thread from the bobbin until the reversal in the direction of the winding of the thread on the bobbin is reached, through the tendency of the bobbin to rotate the sleeve, the wing is maintained substantially in the position shown in Figs. 11 and 12, in engagement with a shoulder 167 formed on the end wall of the bobbin case. Upon the rotation of the bobbin in the reverse direction, as indicated by the arrows in Figs. 14 and 15, produced by the drawing of the thread from

the bobbin after the point of reversal in the direction of the winding of the thread is reached, the sleeve is rotated by the bobbin to swing the wing into the position shown in Fig. 15.

- 10 The mechanism for indicating the condition of the bobbin thread supply and for ejecting the bobbin comprises a lever 168 pivoted on a shaft 170 and having a bobbin 15 ejecting arm 172 located at the rear of the bobbin case and extending forwardly toward the same, the forward end of which is arranged to enter an opening in the end wall of the bobbin case and engage the bobbin.
- 15 The lever 168 normally occupies the position shown in Fig. 4, so that the forward end of the bobbin ejecting arm lies a slight distance back of the rear wall of the bobbin case. Upon stopping the machine the lever 168 is 20 actuated to swing the bobbin ejecting arm forwardly from the position shown in Fig. 4. The wing 166 when in the position shown in Figs. 11 and 12 lies in the path of the end of the bobbin ejecting arm and is 25 engaged by the end of the arm as the arm swings forwardly and acts as a detent to limit the forward movement of the arm and the movement of the lever 168. Under these conditions the lever 168 is shortly thereafter 30 actuated to swing the arm 172 back to its initial position. When the wing 166 is swung into the position shown in Fig. 15, it lies out of the path of the forward end of the bobbin ejecting arm, and as the arm 35 swings forwardly the end of the arm passes through the opening in the rear wall of the bobbin case and engages the bobbin, the contact of the arm with the bobbin limiting the movement of the arm and the lever 168.
- 40 The arm 172 and the lever 168 thus have a slightly greater range or amplitude of movement with the wing 166 in the latter position than with the wing in the first position. Under these conditions the lever 168 is shortly 45 thereafter positively actuated to swing the bobbin ejecting arm still farther forwardly to eject the bobbin from the bobbin holding sleeve 164. The arm 172 in connection with the wing 166 thus act as detecting 50 devices to detect the condition of the bobbin thread supply.
- 55 In the present embodiment of the invention the movements of the lever 168 are derived through suitable connections from the movements of the lock bolt carrier. The lever 168 is actuated to advance and retract the bobbin ejecting arm 172 by means of an endwise movable rod 174 secured at its forward end in a sleeve 176 pivotally connected by means of a stud 178 with the lever and supported at its rear end by an arm 180 on the frame having a slot to receive a block 182 formed on the end of the rod. An actuating sleeve 184 is mounted on the rod 60 65 174 for movement longitudinally of the rod,

and a coiled spring 186 is mounted on the rod within the sleeve, the spring being interposed between washers 188 and 190 mounted on the rod. The opening in the forward end wall of the sleeve 184 is formed to allow the rear end of the sleeve 176 to be projected through said opening, as shown in Fig. 9, while the opening in the rear end wall of the sleeve 184 is formed to receive the block 182, as shown in Figs. 7 and 8. 70 The washer 188 is arranged to engage either the rear end of the sleeve 176 or the inwardly projecting forward end wall of the sleeve 184, and the washer 190 is arranged to engage either the forward end of the block 182 or the inwardly projecting rear end wall of the sleeve 184. The sleeve 184 and rod 174 normally occupy the relative positions shown in Fig. 4. With this construction relative longitudinal movements of the sleeve and rod in either direction will compress the coiled spring 186. The sleeve 184 is moved longitudinally by means of a lever 192 pivoted on a stud 194 and having a fork 196 secured to one arm thereof which embraces the sleeve 184 and engages between flanges 198 formed on the sleeve. The pivot stud 194 is carried by the spaced arms of a carrier 200 secured to the forward end of a stud 202 mounted to slide in a suitable bearing in the frame of the machine. The rear end of the stud 202 is surrounded by a coiled spring 204 interposed between the frame and a nut 206 mounted on the rear end of the stud. The spring normally holds the carrier 200 in its limiting position in engagement with the frame and allows the stud 202 to move forwardly in its bearing in the frame during certain movements of the lever 192. The forked end of the shorter arm of the lever 192 embraces a collar 208 mounted on the forward end of the lock bolt carrier 80, and engages between flanges 210 formed on the collar. The collar 208 is threaded on the forward end of the lock bolt carrier so that it may be adjusted longitudinally thereof, and is secured in adjusted position by means of a lock nut 212. 100 105 110 115 120 125 130

The parts above described normally occupy the positions shown in Fig. 4, with the forward end of the bobbin ejecting arm retracted from the rear end of the bobbin case, the position of the lever 168 being determined by the engagement of a projection 214 on the lever with a stop face on the frame. Upon stopping the machine as the lock bolt carrier moves forwardly after the engagement of the slow speed clutch, the lever 192 is actuated to move the sleeve 184 rearwardly. This movement of the sleeve tends to actuate the rod 174 and the lever 168 to swing the bobbin ejecting arm 172 forwardly. At the time that the forward movement of the lock bolt carrier occurs, a loop of needle thread is being passed about 130

the bobbin case, and in order that the bobbin ejecting arm may not interfere with the passage of the loop about the bobbin case, the forward movement of the arm is delayed until after the loop is drawn from about the bobbin case by the action of the take-up. To secure this result the block 182 at the rear end of the rod 174 is arranged to engage the periphery of a cam disk 216 mounted on the countershaft 134, to prevent the rod from moving rearwardly with the sleeve 184 as the sleeve is actuated by the forward movement of the lock bolt carrier. The rearward movement of the sleeve, therefore, compresses the coiled spring 186, as shown in Fig. 8. The cam disk 216, however, is formed with a recess 218 in its periphery, into which the rear end of the block 182 can enter at a certain point in the rotation of the cam disk. When the recess 218 reaches the block 182, the rod 174 moves rearwardly under the influence of the coiled spring 186, thereby actuating the lever 168 to swing the bobbin ejecting arm 172 forwardly into contact either with the wing 166 or with the bobbin. The recess 218 is located on the cam disk 216 so that the forward movement of the bobbin ejecting arm does not occur until after the loop of needle thread has been drawn from about the bobbin case by the take-up. The forward movement of the sleeve 184 produced through the lever 192 by the rearward movement of the lock bolt carrier tends to actuate the lever 192 produced by the rearward movement of the lock bolt carrier will actuate the lever 168 to swing the bobbin ejecting arm forwardly from the position shown in Fig. 8 to push the bobbin from the bobbin holding sleeve, as shown in Fig. 9. This latch, indicated at 220, is pivoted at 222 on an arm of the lever 168, and is formed with a shoulder or abutment 224 for engagement with the forward face of a block 226 formed at the end of the longer arm of the lever 192. The latch 220 is acted upon by a spring 228 which tends to swing the latch upwardly into acting position. With the wing 166 in the position shown in Figs. 11 and 12, the lever 168 as it is actuated to swing the bobbin ejecting arm forwardly from its normal position does not move far enough to carry the abutment 224 on the latch 220 in front of the block 226 on the lever 192, but the movement of the lever 168 is arrested by the contact of the forward end of the bobbin ejecting arm with the wing, with the parts substantially in the position shown in Fig. 7. Under these conditions, during the movement of the

lever 192 produced by the rearward movement of the lock bolt carrier, the block 226 will move idly along the upper edge of the latch 220 and the rod 174 and the lever 168 will be actuated by the forward movement 70 of the sleeve 184 to retract the bobbin ejector arm to its normal position. With the wing 166 in the position shown in Fig. 15, the movement of the lever 168 as it is actuated to swing the bobbin ejector arm forwardly from its normal position is sufficient to carry the abutment 224 on the latch in front of the block 226. Under these conditions, as the lever 192 is actuated by the rearward movement of the lock bolt carrier, 80 the lever 168 is actuated through the latch to swing the bobbin ejecting arm forwardly from the position shown in Fig. 8 to push the bobbin from the bobbin-holding sleeve, as shown in Fig. 9. This latter figure 85 shows the positions of the parts just before the bobbin ejecting arm has completed its bobbin ejecting movement. The bobbin ejecting arm may act during this bobbin ejecting movement merely to push the bobbin off the bobbin-holding sleeve. Preferably, however, the action of the arm is such as to project the bobbin from within the loop-taker.

The movement of the latch 220 relative to the lever 168 under the influence of the spring 228 is limited by the engagement of a stop shoulder 230 formed on the latch with the lever. This stop shoulder is located on the latch so that as the lever 168 is actuated 95 to swing the bobbin ejecting arm forwardly to eject the bobbin, the acting end of the latch will be actuated downwardly to disengage the abutment 224 on the latch from the block 226, just before the block reaches the limit of its forward movement. During the bobbin ejecting movement of the lever 168 the coiled spring 186 is compressed, as shown clearly in Fig. 9, and upon the disengagement of the abutment 224 on the latch from the block 226, the coiled spring 100 105 110 115 120 125 130 186 moves the rod 174 forwardly, thereby actuating the lever 168 to swing the bobbin ejecting arm back to its normal position.

The devices for controlling the movement of the lock bolt carrier may be adjusted to cause the carrier to move longitudinally to different extents. In order that the block 226 may move rearwardly to substantially the same position regardless of the extent of the forward movement of the lock bolt carrier, an abutment screw 232 is threaded into a projection on the lever 192 and is arranged to engage an abutment face 234 on the frame of the machine to limit the rearward movement of the right-hand end of the lever. The coiled spring 204 allows the carrier 200 to move forwardly during the actuation of the lever 192 by the forward movement of the lock bolt carrier after the

abutment screw 232 engages the abutment face 234.

In sewing outsoles to the welts of a series of shoes upon a machine having the construction described above, starting with a full bobbin inserted in the bobbin holder, the bobbin ejecting mechanism will remain inactive upon each stoppage of the machine at the completion of a seam as long as the bobbin contains sufficient thread to sew a seam about a single shoe. After a number of shoes have been sewn it finally happens that during the sewing of a seam the drawing of the thread from the bobbin reduces the thread supply left on the bobbin below the amount required for the formation of another seam. When this occurs, the bobbin ejecting mechanism, upon stopping the machine at the completion of the seam, is thrown into operation and operates to eject the bobbin from the bobbin case. This gives to the operator an unmistakable signal that there is not sufficient bobbin thread left for the sewing of another seam, and that the bobbin thread supply should be replenished before another seam is started. The empty bobbin having been ejected from the bobbin case, the replenishment of the bobbin thread supply may be quickly and easily effected, this operation requiring merely the insertion of a full bobbin in the bobbin case and the threading of the bobbin case.

Having explained the nature and object of the invention and having specifically described a machine embodying the various features of the invention in their preferred forms, what is claimed is:

1. A sewing machine, having, in combination, stitch forming devices, a bodily stationary thread supply holder, and movable mechanism controlled from the thread on the supply holder for indicating when less than a predetermined amount of thread is left on the supply holder.
- 45 2. A lockstitch sewing machine, having, in combination, stitch forming devices including a needle, a loop taker, a bobbin, and movable mechanism controlled from the thread on the bobbin for indicating when any quantity less than a predetermined amount of thread is left on the bobbin.
- 50 3. A sewing machine, having, in combination, stitch forming devices, a bodily stationary thread supply holder, and movable detector mechanism controlled from the thread on the supply holder and operating to detect when less than a predetermined amount of thread is left on the supply holder.
- 55 4. A sewing machine, having, in combination, stitch forming devices, a thread supply holder, and movable detector mechanism controlled from the thread on the supply holder for detecting the condition of the thread supply on the supply holder thrown

into operation upon each stoppage of the machine.

5. A lockstitch sewing machine, having, in combination, stitch forming devices including a needle, a loop taker, a bobbin, and movable detector mechanism controlled from the thread on the bobbin and operating to detect when any quantity less than a predetermined amount of thread is left on the bobbin. 75

6. A sewing machine, having, in combination, stitch forming devices, a bodily stationary thread supply holder, and movable mechanism controlled from the thread on the supply holder, for indicating the condition of the thread supply on the supply holder before the thread is actually exhausted. 80

7. A lockstitch sewing machine, having, in combination, stitch forming devices including a needle, a bobbin holder, a bobbin, and means for automatically ejecting the bobbin from the bobbin holder. 85

8. A lockstitch sewing machine, having, in combination, stitch forming devices including a needle, a bobbin holder, a bobbin, and means for automatically ejecting the bobbin from the bobbin holder when less than a predetermined amount of thread is left on the bobbin. 90

9. A lockstitch sewing machine, having, in combination, stitch forming devices including a needle, a bobbin holder, a bobbin, and means controlled from the bobbin thread for automatically ejecting the bobbin from the bobbin holder. 95

10. A sewing machine, having, in combination, stitch forming devices, a thread supply holder, an indicating mechanism for indicating the condition of the thread supply on the supply holder, and means for rendering said mechanism inoperative while the supply holder is rotating in one direction, and for rendering the same operative when the direction of rotation of the supply holder is reversed. 105

11. A sewing machine, having, in combination, stitch forming devices, a thread supply holder, and indicating mechanism for indicating the condition of the thread supply controlled by the rotation of the supply holder. 115

12. A lockstitch sewing machine, having, in combination, stitch forming devices including a needle, a loop taker, a bobbin, an indicating mechanism for indicating the condition of the thread supply on the bobbin, and means for rendering said mechanism inoperative while the bobbin is rotating in one direction and for rendering the same operative when the direction of rotation of the bobbin is reversed. 120

13. A lockstitch sewing machine, having, in combination, stitch forming devices, including a needle, a loop taker, a bobbin, and 125

indicating mechanism for indicating the condition of the thread supply on the bobbin controlled by the rotation of the bobbin.

14. A sewing machine, having, in combination, stitch forming devices, a thread supply holder, and normally inactive indicating mechanism controlled from the thread and arranged to be thrown into operation upon stopping the machine for indicating 10 the condition of the thread supply.

15. A lockstitch sewing machine, having, in combination, stitch forming devices including a needle, a loop taker, a bobbin, and normally inactive indicating mechanism controlled from the bobbin thread and arranged to be thrown into operation upon stopping the machine for indicating the condition of the bobbin thread supply.

16. A lockstitch sewing machine, having, 20 in combination, stitch forming devices including a needle, a bobbin holder, a bobbin, and means controlled from the bobbin thread and rendered active upon stopping the machine for ejecting the bobbin from the bobbin holder.

17. A sewing machine, having, in combination, stitch forming devices, a thread supply holder, and means rendered active upon stopping the machine when the thread supply 30 holder contains less than a predetermined amount of thread for indicating the condition of the thread supply.

18. A lockstitch sewing machine, having, in combination, stitch forming devices including a needle, a bobbin holder, a bobbin, and means rendered active upon stopping the machine when the bobbin contains less than a predetermined amount of thread for indicating the condition of the bobbin 40 thread supply.

19. A lockstitch sewing machine, having, in combination, stitch forming devices including a needle, a bobbin holder, a bobbin, and means rendered active upon stopping the machine when the bobbin contains less than a predetermined amount of thread for ejecting the bobbin from the bobbin holder.

20. A sewing machine having, in combination, stitch forming devices, a thread supply holder, a detector mechanism for detecting the condition of the thread supply on the supply holder comprising a movable arm, a thread controlled detent for limiting the movement of said arm normally located 50 in position to engage the arm, and adapted to be moved out of acting position when less than a predetermined amount of thread is left on the supply holder, means operating to advance the arm beyond the detent when 55 the detent is moved out of acting position, and means rendered active by the advance of the arm beyond the detent.

21. A sewing machine having, in combination, stitch forming devices, a thread supply 60 holder, a detector mechanism for detecting

the condition of the thread supply on the supply holder comprising a movable arm, a detent controlled by the rotation of the supply holder for limiting the movement of said arm normally located in position to engage the arm and adapted to be moved out of acting position when less than a predetermined amount of thread is left on the supply holder, means operating to advance the arm beyond the detent when the detent 70 is moved out of acting position, and means rendered active by the advance of the arm beyond the detent.

22. A lockstitch sewing machine having, in combination, stitch forming devices, including a needle, a bobbin holder, a bobbin, a detector mechanism for detecting the condition of the thread supply on the bobbin comprising a movable arm, means for moving the arm toward and from the bobbin at 80 intervals, a thread controlled detent for limiting the movement of the arm toward the bobbin normally located in position to engage the arm and adapted to be moved out of acting position when less than a predetermined amount of thread is left on the bobbin, and means operating to advance the arm beyond the detent.

23. A lockstitch sewing machine having, in combination, stitch forming devices including a needle, a bobbin holder, a bobbin, a detector mechanism for detecting the condition of the thread supply on the bobbin comprising a movable arm, means for moving the arm toward and from the bobbin at 90 intervals, a detent controlled by the rotation of the bobbin for limiting the movement of the arm toward the bobbin normally located in position to engage the arm and adapted to be moved out of acting position when less than a predetermined amount of thread is left on the bobbin, and means operating to eject the bobbin from the bobbin holder when the arm advances beyond the detent.

24. A sewing machine having, in combination, stitch forming devices, a bodily stationary thread supply holder, a detector mechanism for detecting the condition of the thread supply on the supply holder before the actual exhaustion of the thread, and means controlled by the detector mechanism.

25. A sewing machine having, in combination, stitch forming devices, a thread supply holder, and an indicating mechanism arranged to be held out of operation while the supply holder contains more than a predetermined quantity of thread, and adapted to be thrown into operation at any time after the thread on the supply holder is reduced to an amount less than the predetermined quantity.

26. A sewing machine having, in combination, stitch forming devices, a thread supply holder, mechanism arranged normally to remain inactive and to be actuated when, in the course of the drawing of the thread from the supply, the point is reached at which a predetermined positive quantity of thread is left on the holder, and indicating means controlled by said mechanism. 50
- 5 27. A sewing machine having, in combination, stitch forming devices, a thread supply holder, mechanism for indicating the condition of the thread supply, and means for rendering said mechanism active when the thread on the supply holder is less than the amount required for a given length of seam. 55
- 10 28. A lockstitch sewing machine having, in combination, stitch forming devices including a needle, a loop taker, a bobbin, and means rendered operative by a reversal in the direction of rotation of the bobbin for indicating the amount of thread on the bobbin. 60
- 15 29. A machine for sewing seams of predetermined length having, in combination, stitch forming devices, a thread supply holder, and means actuated at the completion of a seam to indicate that the thread on the supply holder is less than the amount required for the next seam. 65
- 20 30. A lockstitch outsole shoe sewing machine having, in combination, stitch forming devices including a needle, a loop taker, a bobbin, and means actuated at the completion of the sewing of a shoe to indicate that the thread on the bobbin is less than the amount required for sewing the next shoe. 70
- 25 31. A lockstitch sewing machine having, in combination, stitch forming devices including a needle, a loop taker, a bobbin having a portion of the thread thereon wound in one direction and the remainder of the thread wound in the opposite direction, and means for indicating a reversal in the direction of rotation of the bobbin. 75
- 30 32. A lockstitch sewing machine having, in combination, stitch forming devices including a needle, a loop taker, a bobbin having a portion of the thread thereon wound in one direction and the remainder of the thread wound in the opposite direction, and means for indicating a reversal in the direction of rotation of the bobbin. 80
- 35 33. A lockstitch outsole shoe sewing machine having, in combination, stitch forming devices including a needle, a loop taker, a bobbin having a portion of the thread, sufficient to sew a seam of predetermined length, wound thereon in one direction and arranged to be drawn last from the bobbin and the remainder of the thread wound thereon in the opposite direction, and means for indicating a reversal in the direction of rotation of the bobbin. 85
- 40 34. A sewing machine having, in combination, stitch forming devices, a thread supply holder, and means actuated on stopping the machine to indicate the condition of the thread supply. 90
- 45 35. A sewing machine having, in combination, stitch forming devices, a thread supply holder, devices for indicating the condition of the thread supply, and means for actuating said devices on stopping the machine. 95
- 50 36. A lockstitch sewing machine having, in combination, stitch forming devices including a needle, a bobbin holder, a bobbin, stop mechanism for stopping the machine with its parts in predetermined position, and means for ejecting the bobbin from the bobbin holder. 100
- 55 37. A lockstitch sewing machine having, in combination, stitch forming devices including a needle, a bobbin holder, a bobbin, stop mechanism for stopping the machine with its parts in predetermined position, and devices actuated from the stop mechanism for ejecting the bobbin from the bobbin holder. 105
